Geo. Nielder of New York City
Setters Patent

Marked to in the Sillers Patent and making part of
the same containing a description in the words of the said Sillers
Nielder himself of his improvement being a Machine for sweeping
Streets, and at the same time removing the dirt.

To all to whom these presents shall come. Be it known that
Geo. Nielder of the City, County and Hall of New York have inven-
ted a new and useful improvement in a Machine for sweeping Streets
and at the same time removing the dirt. and that the following is a
full and exact description of the construction and operation of said
Machine as invented by me. It consists of a wagon the
hind wheels of which being high for the purpose of giving elevation
to the body or dirt receiver are fastened to an iron axle which
turns with them. The fore wheels are proportionately low and
having a short axle they work beneath the frame or beams of
the wagon. This arrangement of the fore wheels is designed to
admit the wagon to make short turns. Upon the axle of these
wheels rests the wagon frame much in the manner of other wagons,
but unlike them, the receiver is built under instead of above
the beams, bringing it near the ground thereby requiring only
a small elevation for the dirt to be raised, for this purpose
the receiver is spanned into the side beams on the under side
between the fore and hind axles as near the bottom as other
parts of the machine will allow; and at such distance from the fore-
axle as will admit the fore wheels in turning to pass without in-
terfering. The bottom of the receiver is constructed of several long
boards, filling the spaces between the cross beams of it. These
boards are combined for the purpose of supporting the receiver
when loaded, the bottom being far enough from the ground
to answer this design. The hind hind axles, fore and form-
ing an angle of about 45 degrees, making an inclined plane

The side boards, extend beyond the rest of the carriage in rear of the hind axle, so far as the shaft of the broom will admit, said broom to be hereafter described.

2nd A revolving cylindrical broom resembling a water-wheel and consisting of eight or any convenient number of combs, of brush bristle or com or any suitable substance made by weaving together the bristles with cord or other means, and fastening them to the broom shape by placing them between bevelled or wedge-shaped beams, or flanks, which beams are fastened to the shaft by bolts, which are fixed to collars on the shaft and passing thru the beams, have on their upper ends screws or a which will work forcing the beams to the centre and firmly wedging the combs. There are other ways of making the broom as, by confining the the bristles of the brush between the clamps, by many bolts and fastening them to iron heads fixed on the shaft near the ends. This broom is placed in a frame made of two strong arms, fastened at their ends by cross pieces of sufficient length to admit the combs between the arms. This frame with the broom parallel to the hind axle and as near to it as will admit is attached to the wagon by fastening one end of each arm to the axle between the beam & scare by means of a hinge box keyed for the purpose of admitting the broom to be detached from the wagon at pleasure, and ^{the top of} the same time, admitting the arms to rise or fall at the opposite ends, which arrangement allows the broom to be elevated or depressed so as to sweep lightly or heavily upon the streets, or be raised from them entirely in circumstances may require. And this is done by levers (it may be done by pulleys or other power) which levers one to each arm are fixed to the side wagon-beams on ^{opposite of} the side by a kind of bolts which answer the fastening placed a little in the rear of the hind axle. The short ends of the levers, with a center on each will support the wooden side of the broom arms. The long ends extend along the

sides of the wagon as far as the front of the receiver and are fastened by a cross piece into which is framed a bar or handle and with this handle the driver who stands upon a platform in front of the receiver controls the broom; at one end of the broom shaft outside of the arm is a pinion wheel into which works a cog wheel that is fastened upon and turns with the hand wagon axle by which a like motion is given to the broom reverse to the motion of the wagon wheels from which the power is communicated. The broom making about three revolutions to one of the wagon wheels. Similar gearing of machinery may be attached to both ends of the broom, or the same motion may be given to it by means of a propeller or similar contrivance. 3. An inclined plane or drag which is made in sections of many pieces of wood or any suitable substance, the sections about the dimensions of two and a half feet long two inches thick and three inches wide, all jointed and having the ends designed to drag on the ground fastened on the underside to nearly sharpness, and the other ends being perforated the sections are placed on an iron rod in such numbers as will together make a plane as wide as the broom is long, and are designed to rock on the rod as a common center of motion adapting themselves to the inequalities of the ground or pavements, any part of them rising or falling without moving any of the others. The drag is placed under the front part of the broom, the other end is fastened by the above named rod to the side brack of the receiver just over the lower end of the plane made by the hand board. This made by the hand board thus making from the ground under the broom to the top of the receiver a continued plane which is designed as a way or passage for the dirt. On an inclined plane is made from the drag by a rising upon it a long round a roller placed just under the upper end of the drag and round over the roller placed on two posts raised above the top of the receiver on the side beams. These rollers and

consequently the arms are turned by a band passing over a wheel on the end of the upper roller, and over another wheel on the hind axle where it receives its motion. The motion of the broom in turning sweeps the ground or pavements, and carrying the dirt along with it on the drag sweeps a large portion of that also and gives ^{the} ~~the~~ impulse which causes it beyond the drag up the inclined plane of the hind board into the receiver, and carries the dirt on to the platform for the elevators which turning conveys it off into the receiver. Thus sweeping and taking up the dirt at the same time.

The operation of taking up the dirt is greatly assisted by the air which is formed into a strong current by the motion of the broom which acts as a forming mill, and for this purpose a channel is made from the broom by connecting the extreme ^{extremest} ~~extremest~~ of the drag with the sides of the receiver by means of a gore of leather or other matter, and making a covering from the broom over the drag, and the receiver, the broom is also covered. But that the air may pass from the receiver without producing dust in sweeping, a kind of flue is made conducting the air which is driven out of the top of the receiver thro an opening for that purpose near the front back over the receiver cover to the broom thus forming a continued circuit. Across the under side of the drag runs an iron rod fastened to the extreme ^{extremest} ~~extremest~~ which rod is confined by a small chain to the box above described in such a manner as to raise the drag from the ground with the broom at pleasure, when it is not necessary to sweep.

The whole machine is to be worked by horse or other power, the receiver being filled with dirt the broom is detached by means of the keyed box above mentioned and placed on another wagon while the loaded one is taken away to be disposed of. What I claim as my invention is the application of the cylindrical sweeping broom to the purpose of en-

7777

277

ing the streets and taking the dirt at the same time attached to
the wagon with the shaft parallel to the axis of the wheel or
wheels by which it is moved, the receiving motion being the
reverse of the receding motion of said wheel or wheels, and
being fixed on supports in such manner that by mechanical
means it may be elevated or depressed at pleasure
so as to press heavily or lightly upon the streets or be raised
from them entirely as circumstances may require, upon the
principles herein before set forth. I also claim the drag
formed in sections and moving as before described on a common
center so as to adapt itself to the inequalities of the streets
or pavements, parts thereof rising or falling without effecting
the rest and designed as a way or passage for raising the dirt
which it is so placed as to receive the same, and the ad-
mission of the air in the manner above described, together
with the adaptation of all the parts of the machine to
the particular object of raising and of taking up and dischar-
ging dirt in the manner described above.
